UNITED STATES PATENT OFFICE.

JOHN G. PEACE, OF SALEM, MISSOURI.

UMBRELLA.

SPECIFICATION forming part of Letters Patent No. 269,317, dated December 19, 1882.

Application filed September 2, 1882. (No model.)

To all whom it may concern:

Be it known that I, JOHN G. PEACE, of Salem, in the county of Dent and State of Missouri, have invented a certain new and useful Improvement in Umbrellas, of which the following is a specification, reference being had to the accompanying drawings, forming part of the same.

Figure 1 is an under perspective view. Fig. 10 2 is an axial section. Fig. 3 is a detail section at 3 3, Fig. 2, enlarged.

My improvement consists of an umbrella whose ribs consist of collapsible tubes of rubber cloth or other suitable material impervious to air. In the form shown and described the inner ends of the tubes communicate with a central chamber, through which a tubular staff or handle passes, at whose lower end is a force-pump, by which air is forced through 20 the handle into the chamber and the ribs to expand the umbrella.

The umbrella-cover may be of rubber cloth, or of any other suitable material secured to the ribs in any suitable way.

25 A is the staff, made of a number of tubular sections, *a*, fitted together with air-tight joints. Thus an air-tight tube is formed that may be taken apart when it is desired to fold up the umbrella in a small compass.

30 B is a plunger, of tubular construction, working in the tubular handle A'.

a' is a rubber or other packing-ring, preventing the escape of air between the plunger B and cylindrical handle A'.

35 B' is a knob by which the plunger B is operated, the knob having an air-passage, *b'*, in communication with the bore of the plunger, to admit air to the same.

b is a ball-valve at the upper or inner end 40 of the plunger, opening inward.

*a*² is a check-valve in the cylindrical handle A', to prevent the escape of air from the interior of the staff. The valve *a*², like *b*, is shown of ball form, it being proposed to use

45 rubber balls for the valves; but other forms of valves may be used.

The staff passes centrally through a chamber, C, made of rubber cloth or other flexible material impervious to the air. This chamber

is in form of a double convex lens. The staff 50 passes through the walls of the chamber with air-tight joints. I show the cloth turned out in short nipples *c*, embracing the staff, and secured by encircling ties *c'*, of wire or cord. The ties may be hidden by collars, one of which is 55 shown at *c'*. The upper end of the staff is closed to prevent the escape of air. The part of the staff within the chamber C has perforations *a*³, through which air may enter or leave the chamber.

60 D are ribs extending radially from the edge of the chamber. These ribs are tubular and made preferably tapering toward the outer end, the inner portions requiring more rigidity than the outer. The outer ends of the 65 ribs are closed, and their inner ends communicate with the interior of the chamber C, so that the inflation of the chamber causes the inflation of the ribs and causes them to stand out with sufficient rigidity to support the 70 cover E.

The cover E may be made of any material in common use for umbrellas, secured to the ribs in any suitable manner.

75 When it is desired to fold or roll up the umbrella the sections *a* of the staff are taken apart, which allows the escape of the air from the chamber C and ribs D, and the whole may be folded into a parcel of very small bulk.

I claim as my invention—

80 1. An umbrella having tubular ribs made of rubber cloth or equivalent flexible material.
2. An umbrella having tubular ribs, substantially as set forth, and a central collapsible air-chamber in communication with the 85 ribs, substantially as set forth.

3. An umbrella having tubular ribs, a central air-chamber in connection therewith, and a tubular staff connected to and in communication with the said air-chamber.

90 4. In combination with the tubular ribs D, air-chamber C, and staff A, the force-pump A' B, for the purpose set forth.

JOHN G. PEACE.
